10 Claims. (Cl. 222—448)

ABSTRACT OF THE DISCLOSURE

A liquid dispensing apparatus having a measuring chamber including an elongated filling tube with a variable orifice valve at its inlet end and a foot valve at its discharge end. Pressure responsive means is connected to the valves to open the foot valve in response to increased pressure within the chamber while the variable orifice valve maintains uniform pressure on the pressure responsive means preventing chattering of the foot valve at both high and low flow rates. The apparatus also includes a suction creating check valve which assures proper collapse of a flexible sleeve in the valve.

The present invention pertains to liquid dispensing apparatus and more particularly relates to a positive displacement filling apparatus for filling a predetermined volume of liquid, such as milk, into a container.

Certain well known carton forming and filling apparatus require filling apparatus which is capable of rapidly filling predetermined volumes of liquid into different sized cartons, such as: quart, pint, $\frac{1}{3}$ quart, or $\frac{1}{2}$ pint cartons. The liquid dispensing apparatus of the present invention is intended for use in such a prior art apparatus.

Although the above-referred-to prior art filling apparatus operates quite satisfactorily at a rate of approximately 110 cartons per minute, its operation is not satisfactory when the filling rate is increased to between approximately 150 and 200 cartons per minute. When filling cartons at these higher rates and when utilizing liquid pressure within a measuring chamber to selectively open and close the foot valve, it has been discovered that an orifice of variable size must be inserted between the foot valve and the pressure sensitive element which controls the opening and closing of the valve. It has been found that the use of an orifice of fixed size which is large enough to accommodate the higher rates of flow through the filling apparatus will not provide a sufficient back pressure within the apparatus to hold the foot valve open during slower rates of flow thereby causing the foot valve to chatter at these slower flow rates. Thus, when using no orifice or when using an orifice large enough to accommodate the rapid flow rates which are necessary when filling large cartons at the rate of 150 to 200 cartons per minute, the foot valve will chatter at the slower rates of liquid flow through the measuring chamber. Such slow flow rates occur when filling smaller cartons or when introducing the initial quantity of liquid into larger cartons in a prefilling step to be described hereinafter. If chattering of the foot valve is permitted air entrained in the liquid or drawn into the liquid through the foot valve will result in objectionable foaming of the liquid.

If a fixed orifice is used that is small enough to assure proper opening of the foot valve at the slower rates of liquid flow through the measuring chamber, as when filling smaller cartons or when performing the prefilling step on larger cartons, it has been found that the orifice is not sufficiently large to accommodate the higher rates of flow resulting in such an excessive build up of pressure within the measuring chamber as to render the filling apparatus inoperative at the higher liquid flow rates through the chamber.

2

It has been discovered that the higher rates also cause inwardly opening foot valves to draw a bubble of air into the filling apparatus during the initial opening of the foot valve with the result that considerable foaming occurs during the high speed filling operation.

It is therefore an object of the present invention to provide an improved liquid filling or dispensing apparatus.

Another object is to provide a liquid dispensing apparatus having a variable orifice valve therein for first establishing a foot valve opening back pressure and for thereafter permitting liquid to flow therewith at velocities sufficient to fill either large or small cartons while maintaining very accurate regulation of the quantity of liquid delivered.

Another object is to provide a vacuum creating system wherein a flexible sleeve is held from collapsing into a volumetric measuring chamber during the filling operation, thereby maintaining accurate regulation of the quantity of liquid being delivered to the container.

Another object is to provide a flexible sleeve which, when in the extended position, will release any air trapped therein during the previous filling stroke thereby assuring that an exact measured quantity of liquid will be present in the measuring chamber each time a filling stroke is initiated.

These and other objects and advantages of the present invention will become apparent from the following description and the accompanying drawings, in which:

FIGURE 1 is a vertical elevation taken through the liquid dispensing apparatus of the present invention, certain valve actuating elements being diagrammatically illustrated and other elements being shown in vertical central section.

FIGURE 2 is an enlarged vertical central section of the lower portion of the apparatus of FIGURE 1 with the inlet valve being open and the foot valve being closed, certain parts being broken away.

FIGURE 3 is a section similar to FIGURE 2 but illustrating the foot valve in an open position and the inlet valve in a closed position, and with the inlet valve moved downwardly an amount sufficient to discharge a quantity of liquid into the carton sufficient to cover the lower end of the filling tube, certain parts being broken away.

FIGURE 4 is an enlarged vertical central section of an upper portion of the apparatus of FIGURE 1 illustrating the inlet valve in an open position and a sleeve vacuumizing device with the sleeve being shown in its fully extended position.

FIGURE 5 is a section similar to FIGURE 4 but illustrating the sleeve in an intermediate position.

FIGURE 6 is a vertical central section of a turret upon which a plurality of filling valves of the present invention are mounted, only two valves being illustrated therein.

Each of a plurality of liquid dispensing apparatus 10 (only two being shown in FIG. 6) of the present invention is bolted to an outlet opening 12 of a liquid supply tank 14 which is supported upon the upper end of a turret 15.

In general, the turret 15 comprises a stationary vertical column 16 which rotatably supports the tank 14 and a stabilizing wheel 17 near its upper end, and rotatably supports a sprocket 18 and a lower stabilizing wheel 19 near its lower end. A continuously driven conveyor 20 is provided with evenly spaced carriers 21 thereon, each carrier being adapted to support a carton C in alignment with an associated dispensing apparatus 10 as the carton and the dispensing apparatus 10 are moved around the axis of the column 16, which axis defines the axis of rotation of the turret 15. The sprocket 18 is connected in driving engagement to the lower stabilizing wheel 19 by a drive post 22 and the lower stabilizing wheel 19 is connected to the upper stabilizing wheel 17 and to the tank

14 by a plurality of evenly spaced vertically extending inner guide rods 23 and a plurality of equally spaced vertically extending outer guide rods 24. As clearly shown on the right side of FIGURE 6, each dispensing apparatus 10 is provided with two cam actuated arms 25 and 26 which are guided for vertical movement during the filling operation by one of the rods 23 and by one of the rods 24. An upper non-rotatable cam 27 is rigidly secured to the stationary column 16 and cooperates with the upper arm 25 to vertically reciprocate a first portion of each dispensing apparatus 10, and a lower non-rotatable cam 28 is secured to the stationary column 16 and cooperates with the arm 26 to vertically reciprocate another portion of the dispensing apparatus 10. A large diameter foot valve latching cam ring 29 is mounted in fixed position around the turret 15 outside the path of movement of each dispensing apparatus 10 by one or more brackets 30 and by a utility post 31, which brackets and post are rigidly secured to the frame of the machine. The cam ring 29 is not a truly circular member but rather it includes a small diameter arcuate portion 29a which holds a foot valve of the apparatus 10 closed, and a large diameter portion 29b which permits opening of the foot valve during the filling operation.

It is to be understood that the specific details of the turret 15 form no part of the present invention. If a more detailed description of the turret and its actuating mechanism is desired, reference may be had to the aforementioned Vadas et al. application. It is also to be understood that the dispensing apparatus 10 need not be limited to turret mounted operation as above described, but may also be mounted in a fixed position while cooperating to fill cartons which are intermittently moved therewith.

In general, each liquid dispensing apparatus 10 (FIG. 1) comprises an upper tubular housing 66 having a flanged upper end 68 bolted to and communicating with the tank 14 through one of the openings 12. A generally tubular inlet valve housing 70 has its upper end 70a disposed around the lower end of the housing 66 and sealed thereto by a flexible sleeve 74 which permits vertical movement of the inlet valve housing 70 relative to the upper housing 66. The lower reduced diameter end 70b of the inlet valve housing 70 is provided with an inlet valve 76 which is alternately moved between an open and a closed position by a cam operated actuating device 78. The upper end 80a of a generally tubular liquid measuring housing 80 is slidably received around the lower end 70b of the inlet valve housing 70 for vertical movement relative thereto and is sealed thereto by a flexible sleeve 82. The liquid measuring housing 80 includes a reduced diameter filling tube 84 at its lower end, which filling tube is inserted into a carton C to be filled and has a foot valve 86 at its lower end. The liquid measuring housing 80 defines a variable capacity, volumetric liquid measuring chamber 88 which is at all times filled with liquid. A valve actuating device 90 is operatively connected to the foot valve 86 and responds to an increase of pressure within the measuring chamber 88 to open the foot valve 86, the pressure increase in the chamber 88 being caused by decreasing the size of the chamber 88 by movement of the inlet valve housing 70 and the liquid measuring housing 80 toward each other after the inlet valve 76 has first been closed.

At the beginning of the cycle of operation, the components of the liquid dispensing apparatus are positioned as shown in FIGURE 1 with a carton C to be filled being supported by a carrier 21 directly below the filling tube 84. As illustrated in FIGURES 1 and 6, the inlet valve 76 is held open by a cam follower 92 of the valve actuating device 78 which engages an arcuate lobe 94 on the lower track 96 of the annular cam 27 which cam is concentric with the vertical axis of rotation of the turret-supported liquid supply tank 14. At this time, a cam follower 100 that is journaled on the arm 25 holds the inlet valve housing 70 in its uppermost position by riding along

an upper arcuate track 103 of the cam 27 that is parallel to the lower track 96. A cam follower 104 on the end of the arm 26 which arm is operatively connected to the liquid measuring housing 80, rides along the upper surface of the annular cam 28 which includes adjustable portions (not shown) that may be vertically adjusted so as to control the vertical travel of the measuring housing. Thus, when it is desired to fill different size cartons with predetermined quantities of liquid, both the adjustable portion of the cam and the vertically adjustable carton carrier 21 are raised or lowered to their desired vertical positions by means fully disclosed in the Vadas et al. application. In order to positively hold the foot valve 86 closed during the period when the inlet valve 76 is open, latching means such as the annular cam track 29 is positioned outwardly of the apparatus 10 and engages a portion of the valve actuating device 90 to positively hold the foot valve closed at all times when the inlet valve 76 is open. When the inlet valve is closed, the actuating device 90 enters the portion 29b of the track 29 permitting the valve 86 to open. It will also be understood that when the inlet valve 76 is closed, atmospheric pressure acting on the actuating device 90 will be greater than the negative pressure within the measuring chamber 88 and will hold the foot valve 86 closed until the housings 70 and 80 are moved toward each other to provide a pressure within the measuring chamber 88 that is greater than the pressure outside of the chamber. It will be understood that the cam track 29 maintains a position in horizontal alignment with the actuating device 90.

Upon rotation of the liquid supply tank 14 and liquid dispensing apparatus 10 about the cams 27 and 28, the measuring housing 80 is first lowered to draw liquid through the open inlet valve 76 into the measuring chamber 88 of the liquid measuring housing 80, and to move the filling tube 84 into the carton with its lower end disposed immediately adjacent the bottom closure of the carton. The inlet valve 76 is then closed in response to the cam follower 92 moving off the arcuate lobe 94 of the cam 27. With the inlet valve closed and the actuating mechanism 90 released, continued rotation of the dispensing apparatus 10 about the vertical turret axis causes the inlet valve housing 70 to gradually lower, thereby increasing the pressure in the measuring chamber 88 and causing the foot valve 86 to open, permitting liquid to relatively slowly enter the carton during a prefilling operation to a depth slightly above that of the lower end of the filling tube as indicated in FIGURE 3. The annular cam 28 then rapidly raises the measuring housing 80 while the housing 70 is stationary, thereby reducing the volume of the chamber and causing the liquid to rapidly fill the carton.

After the carton has been filled with the desired quantity of liquid and the lower end of the filling tube 84 is still in the liquid in the carton, relative motion between the inlet housing 70 and the measuring housing 80 ceases, thus again establishing the aforementioned negative pressure within the measuring chamber causing the foot valve 86 to close. After the foot valve has closed, the cams 27 and 28 raise the inlet housing 70 and measuring housing 80 as a unit thereby withdrawing the filling tube from the carton. Shortly after the foot valve has been closed by negative pressure within the measuring chamber 88, the actuating device 90 enters the small diameter arcuate portion 29a of the latching ring 29 thereby latching the foot valve 86 closed until the cycle of operation is completed.

An important feature of the present invention which makes it possible for the liquid dispensing apparatus to operate at the higher rates mentioned above, is the provision of a variable orifice valve 114 in the inlet end of the filling tube 84, which valve 114 cooperates with the foot valve 86 which is designed to open downwardly and outwardly of the filling tube so as to avoid drawing air into the tube. The variable orifice valve 114 and foot valve 86 cooperate to eliminate chattering of the foot

valve during both the relatively slow preliminary filling operation and the small carton filling operation by assuring that sufficient back pressure is retained in the measuring chamber 88 during both preliminary and final filling, and that the flow passages within the dispensing housing 80 are sufficiently open during both preliminary and final filling to accommodate the rate of liquid flow therethrough without loss of accuracy as to the quantity of liquid being discharged into the cartons.

The variable orifice valve 114 comprises an orifice plate 116 (FIGS. 2 and 3) which includes an annular flange 118 formed integrally with an annular dish 120 that is inclined downwardly toward a central circular orifice 122. The orifice plate 116 is press fitted into the upper end of the filling tube 84 and has the upper end of a foot valve 86 extending therethrough. A pair of valve guiding spiders 126 are welded to the rod 124. Each spider includes three equally spaced arms 128 projecting radially outward from the rod 124 and slidably engaging the inside surface of the filling tube 84 to maintain the rod 124 concentric with the tube 84 during vertical movement thereof.

An annular valve head 130 is secured to the rod 124 and is disposed in closed position within the orifice 122 when the foot valve 86 is in a closed position. The valve head 130 includes an upper outwardly and downwardly flared surface 132 and a lower downwardly and inwardly flared surface 134 which connect the outer periphery of the head 130 with the rod 124 and assures a streamlined flow of liquid therewith. It has been found that a radial clearance of between 15-30 thousands of an inch is necessary between the walls of the orifice 122 and the periphery of the valve head 130 to assure that any abnormal buildup of pressure in the portion of the measuring chamber 88 above the orifice valve 114, due to the very high operating speeds, will be transmitted into the portion of the measuring chamber 88 below the orifice valve 114 and the liquid will flow out of the foot valve 86 immediately before the foot valve is closed rather than causing damage to the valve actuating device 90.

The foot valve 86 comprises the rod 124 and a valve head 136 secured to the lower end of the rod. The valve head 136 is of a resilient material such as rubber and comprises a beveled sealing surface 138 which seats against a mating beveled surface 140 formed in the lower end of the filling tube 84 when the orifice valve 114 and foot valve 86 are in closed position. It will be noted that, when the rod 124 is moved downwardly by pressure acting on the valve actuating device 90, the orifice valve 114 and foot valve 86 are both opened, and that the pressure of the fluid flowing past the valves tends to maintain the valves in an open position.

As mentioned previously, the opening and closing of the foot valve 86 and orifice valve 114 is controlled by the valve actuating device 90 (FIGS. 2 and 3). The valve actuating device 90 comprises a centrally apertured flexible diaphragm 146 (FIGS. 2 and 3) which has its outer periphery clamped in fluid tight engagement between a flange 148 surrounding an opening 150 in the liquid measuring housing 80 and a flanged collar 152 by means of a quick release split ring clamp 154. The shank 156 of a generally Z-shaped valve actuating lever 158 projects through the aperture in the diaphragm 146 and through a collar 162 that abuts on the face of the inner periphery of diaphragm 146. A flange 160 formed on the lever 158 abuts the other face of the diaphragm, and a hub of a control lever 164 engages the collar 162. The flange 160, the diaphragm, the collar 162 and the hub of lever 164 are clamped together by a nut 166 that is screwed onto a reduced diameter portion of the shank 156 to provide a fluid tight seal between the diaphragm 146 and the flange 160. The upper end of the pivot control lever 164 is pivotally mounted on a pin 168 which projects outwardly from a bracket 170 that is secured, as by welding, to the flanged collar 152 as illustrated in FIGURE 1.

It will be noted that the actuating device 78 for the inlet valve 76 is substantially the same as the device 90 and, therefore, the device will not be described in detail. It will be noted, however, that the device 78 is urged to the closed position by a spring 172 which is connected between a pivot control lever 174 and a lug 176 secured to the inlet valve housing 70. The pivot control lever 174 is pivoted about a pin 178 secured to the lug 176 and has the cam follower 92 journaled on one end thereof as clearly illustrated in FIGURE 1.

In order to fill an equal quantity of liquid into each carton of a common size during each cycle of operation of the liquid dispensing apparatus 10, it is essential that the size of the measuring chamber 88 be exactly the same for all of the cycles of operation and for each of the several dispensing apparatus 10 carried by the turret 15. It is, therefore, an important feature of the invention to assure that the flexible sleeve 82 will be held firmly against the inner walls of the chamber 88 when the chamber is in its expanded position illustrated in FIGURE 2. It is also essential that any air bubbles which enter the filling tube 84 with the milk or due to the rapid opening of the foot valve 86 will be permitted to flow upwardly out of the measuring chamber 88 prior to the entrapment of the next measured quantity of liquid in the chamber 88.

If air bubbles were permitted to accumulate within the measuring chamber of each of the several dispensing apparatuses 10 mounted on the turret 15, it will be appreciated that the size of the air bubbles would not be the same in each measuring chamber and, accordingly a mechanism, such as the in-motion adjustment mechanism disclosed in the Vadas et al. application, could not be used to accurately compensate for errors in the quantity of liquid filled into the cartons due to the presence of air bubbles of different sizes in the measuring chambers. Furthermore, if air bubbles were permitted to remain in the measuring chambers 88, the inaccuracies would be quite large when filling small cartons since the liquid flow rates through the measuring chambers is relatively slow for small cartons and the pressure within the measuring chambers is correspondingly low. Thus, a trapped bubble of air, which is a compressible fluid, will be much larger when filling small cartons than it would be when the pressure in the chamber is higher as when filling larger cartons.

Accordingly, the upper end 80a of the liquid measuring housing 80 has a lower flanged edge 182 (FIG. 4) clamped to a flanged edge 184 of the housing 80 by a quick release split clamp ring 186. As illustrated in FIGURE 4, the lower end of the sleeve 82 has an enlarged ring 190 formed thereon that is clamped in fluid tight engagement in recesses in the flanges 182 and 184. The upper end (FIG. 4) of the sleeve 82 is provided with an annular flange 192 which is received in an annular slot 194 formed in the lower tubular member 70b of the inlet valve housing 70, and is slightly compressed and held in fluid tight engagement therewith by an outer tubular member 198. The members are connected together near their upper ends by a pin 200 and a cooperating ring 202. The pin 200 is secured to the inner tubular member 70b and is received in a bayonet slot 201 formed in the cooperating retainer ring 202. The slot 201 includes an inclined portion 203 (FIG. 1) which, during assembly, engages the pin and firmly forces the outer tubular member downwardly into clamping engagement with the upper end of the sleeve 82 upon rotation of the retaining ring 202.

The upper end 80a of the liquid measuring housing 80 is provided with an inwardly directed flange 204 at its upper end. An O-ring 206 is fitted in an annular groove 208 in the flange 204 and is slidably received on the outside surface of the member 198 to provide a fluid tight seal. As best shown in FIGURE 5, the flexible sleeve 82, the O-ring 206, the inside surface of the wall 80a and the adjacent outside surface of the member 198 cooperate to

define a variable capacity vacuum chamber 210. A check valve 212 communicates with the vacuum chamber 210 and has a spring loaded ball 214 therein which permits air to be forced out of the vacuum chamber 210 through the check valve 212 but prevents air from entering the chamber 210 through the check valve. Thus, when the measuring housing 80 is moved downwardly to the extended position illustrated in FIGURE 4, substantially all of the air in the vacuum chamber 210 is forced out of the chamber 210 through the check valve 212. During the initial downward preliminary filling stroke of the inlet valve housing 70 relative to the liquid measuring housing 80 and the final upward filling stroke of the measuring housing 80 relative to the inlet housing 70, the check valve 212 prevents air from entering the vacuum chamber 210 thus creating a vacuum therein as the vacuum chamber enlarges. The vacuum causes the flexible sleeve 82 to fold and cling to the outer wall of the outer tubular member 198 and form a loop 82a, as indicated in FIGURE 5, during the carton filling stroke, thereby preventing any volume disturbing accordion folds from occurring in the flexible sleeve 82 which would vary the quantity of liquid discharged from the apparatus 10 during each filling stroke of the liquid dispensing apparatus.

Because the foot valve 86 (FIG. 3) must be opened very rapidly when filling cartons at the rate of between 150 and 200 cartons per minute, a small quantity of air may enter the filling tube 84 and flow upwardly therein during this initial opening of the foot valve 86. This air, which is a compressible fluid, will flow upwardly in the measuring chamber 88, and must be released therefrom in order to prevent the accumulation of air in the chamber 88, which accumulated air would alter the volumetric capacity of the chamber 88. It will be particularly noted that this air will become trapped in the loop 82a (FIG. 5) during the filling operation. In order to assure that all of this trapped air is released from the loop 82a and from the measuring chamber 88 during each cycle of the operation of the liquid dispensing apparatus 10, the loop 82a is completely unfolded when the liquid measuring housing is in its lowermost position, allowing the previously trapped air to flow upwardly past the open inlet valve 76 and be discharged to the atmosphere through the liquid supply tank 14 (FIG. 1).

From the foregoing description, it will be apparent that the liquid dispensing apparatus of the present invention is adapted to operate at a very high rate of speed while accurately discharging a predetermined quantity of liquid during each cycle of operation thereof. The dispensing apparatus features a variable orifice valve which cooperates with a downwardly opening foot valve to eliminate chattering of the foot valve during the filling operation by assuring that the foot valve opening pressure will be sufficient to maintain the foot valve open during both the preliminary and final filling steps. The liquid dispensing apparatus also features a check valve vacuumizing system which assures that the flexible sleeve will be folded in the same manner during each filling stroke and will be unfolded to release entrapped air therefrom when the measuring chamber is in its fully expanded position.

While one embodiment of the present invention has been shown and described, it will be understood that various changes and modifications will be made without departing from the spirit of the invention or the scope of the appended claims.

The invention having thus been described, what is believed to be new and desired to be protected by Letters Patent is:

1. A liquid dispensing apparatus comprising means defining a variable capacity liquid measuring chamber which includes a filling tube having an inlet and an outlet end, means for filling said chamber with a quantity of liquid, means defining an orifice at the inlet end of said filling tube, an orifice valve associated with said orifice and

movable between open and closed positions to vary the size of said orifice progressively from a substantially closed condition to a substantially unrestricted open condition, a foot valve movable between an open position permitting fluid to flow through the outlet end of said filling tube to a closed position, means for decreasing the size of said liquid measuring chamber thereby increasing the pressure within said chamber, and pressure responsive means disposed partially within said measuring chamber for opening said orifice valve and said foot valve in response to the pressure increase in said measuring chamber.

2. An apparatus according to claim 1 wherein said means for decreasing the size of said liquid measuring chamber decreases said chamber size at variable rates thereby increasing the pressure within said chamber, and wherein said means for opening said orifice valve and said foot valve controls the amount of opening of said orifice valve and said foot valve in direct proportion to the pressure increase in said measuring chamber.

3. An apparatus according to claim 1 wherein said foot valve opens outwardly, said actuating means alternately increasing and decreasing the size of said liquid measuring chamber, said chamber filling means being operative to fill the chamber when said chamber is increasing in size, and the outward opening of said foot valve being effective to minimize the amount of air brought into the filling tube during rapid opening of said foot valve.

4. A liquid dispensing apparatus comprising means defining an inlet housing having an outlet end, means for maintaining a supply of liquid in said inlet housing, a liquid measuring housing communicating with said outlet end of said inlet housing and including a filling tube having an inlet end and a discharge end, sealing means connecting said outlet end to said liquid measuring housing for allowing relative movement between said inlet housing and said measuring housing while maintaining a fluid tight connection therebetween, an inlet valve movable between a position closing said outlet end and a position opening said outlet end, means for alternately opening and closing said inlet valve, means defining an orifice at said inlet end of said filling tube, an orifice valve movable between positions wherein the size of the flow passage defined by said orifice and said orifice valve progressively varies from a substantially closed position to a substantially unrestricted open position, a foot valve movable between an open position permitting fluid to flow through the discharge end of said filling tube and a closed position, pressure responsive means disposed partially within said measuring housing for opening said orifice valve and said foot valve when said inlet valve is closed in response to a pressure increase in said measuring housing, the amount of opening of said orifice valve and of said foot valve varying in direct proportion to the increase of pressure in said measuring housing, and means for moving said inlet housing and measuring housing relative to each other when said inlet valve is closed for diminishing the size of said measuring housing thereby increasing the pressure within said measuring housing.

5. A liquid dispensing apparatus according to claim 4 wherein said foot valve opens outwardly away from the discharge end of said filling tube for minimizing the amount of air drawn into said tube during the rapid opening of said valve.

6. An apparatus according to claim 4 including means connecting said orifice valve to said foot valve wherein both valves are simultaneously moved to open positions in response to an increase of pressure within said measuring housing to a pressure substantially greater than atmospheric pressure, said means for moving said measuring housing relative to said inlet housing being arranged to first move said inlet housing in a direction for first increasing the volume of said housing when said inlet valve is open for filling said chamber with a liquid, and to thereafter decrease the volume of said measuring chamber when said inlet valve is closed thereby increasing the pressure

within said measuring housing and causing said orifice valve and said foot valve to open and to discharge a measured quantity of liquid from said filling tube.

7. An apparatus according to claim 4 wherein said inlet housing has a tubular outlet end; said liquid measuring housing has a tubular inlet end disposed in telescoping relation with said tubular outlet end; said sealing means includes a flexible impervious sealing sleeve having one end sealed to said tubular outlet end and the other end sealed to said tubular inlet end, and a sealing element spaced from said sealing sleeve and providing a fluid tight seal between said tubular outlet end and said tubular inlet end; said sealing sleeve and said sealing element cooperating with the adjacent walls of said tubular outlet end and said tubular inlet end to define a variable capacity vacuum chamber; said apparatus additionally comprising a check valve communicating with said vacuum chamber and arranged to permit air to flow out of said vacuum chamber and prevent air from entering said vacuum chamber; said means for moving said inlet housing and said measuring housing relative to each other being effective to alternately enlarge and diminish the size of said chambers, enlargement of said vacuum chamber being effective to create a vacuum in said vacuum chamber which controls the opening of said sealing sleeve by insuring proper folding of said sleeve during telescoping movement of said tubular ends.

8. An apparatus according to claim 7 wherein said sealing element is an O-ring fitted in said tubular inlet

end of said measuring housing and operatively connected in fluid tight sealing engagement with said tubular outlet end of said inlet housing.

9. An apparatus according to claim 7 wherein said flexible sleeve is completely unfolded when said measuring chamber is in its fully enlarged position thereby preventing entrapment of air in said measuring chamber by said flexible sleeve.

10. An apparatus according to claim 2 wherein said foot valve opens outwardly, said actuating means alternately increasing and decreasing the size of said liquid measuring chamber, said chamber filling means being operative to fill the chamber when said chamber is increasing in size, and the outwardly opening of said foot valve being effective to minimize the amount of air brought into the filling tube during rapid opening of said foot valve.
